APPARATUS FOR LOADING TANK CARS AND
THE LIKEHarrison O. Parsons, Houston, Tex., assignor to
Standard Oil Development Company, a corpora-
tion of Delaware

Application November 4, 1930, Serial No. 493,331

4 Claims. (Cl. 220—86)

This invention relates to improvements in apparatus for loading receptacles with liquid, especially tank cars adapted for the transportation of volatile liquids, such as casinghead gasoline. 5 A primary purpose of the invention is to provide simple, rapid, and convenient means for loading, gaging, sampling and discharging tank cars, and the like, without substantial escape of vapors.

In the accompanying drawings, which illustrate a preferred form of the invention,

Fig. 1 is a vertical section, partly broken away, through a tank car equipped with an improved dome cover and appurtenances, the view being taken on line I—I of Fig. 3;

15 Fig. 2 is a vertical section taken on line II—II of Fig. 3; and

Fig. 3 is a top plan view of the improved construction with the dome cover removed.

Referring to the drawings, reference numeral 20 1 indicates the shell of a tank car, or similar receptacle for volatile oil or other liquid which should be handled out of contact with air so far as possible. A dome 2 is secured to the shell 1, and has an opening at the top closed by a valve 25 box 3. The base plate 3a of this box is perforated to receive the loading and unloading lines and the gage pipe, which will be described in detail below.

The loading line 4 passes through the plate 3a 30 and terminates at a point just above the top of the shell, that is, in a line with the liquid when "shellful". Line 4 is connected to an oil tank, or other source, from which the liquid is to be passed into the tank car. A valve 5 is installed 35 in this line and is actuatable by a handle 5a. A vent line 6 extends through plate 3a to a point adjacent the bottom of shell 1. There is a valve 7 in this line, actuatable by a handle 7a. Also installed in vent line 6 is a small pipe 8 which has 40 its open lower end in a plane just above the top of the shell. Line 6 is perforated at 9 so that air may be vented into the dome when oil rises in the line.

A gage pipe 10 extends from plate 3a down- 45 wardly into shell 1 and has at its bottom a gate valve 11, preferably of the quick-acting type. This valve is actuated through a stem 12 which extends into valve box 3. The gage pipe is reduced in diameter at its lower end as shown at 50 13. A screw plug 14 normally closes the upper end of the gage pipe. This plug is hollow and has small openings 15 somewhat below its upper part. When the plug is partially screwed out these openings put the gage pipe into communication with the atmosphere. The gauge pipe

may be opened or closed to pressure within the tank car through a branch pipe 10A, having a valve 16 therein, extending from the upper part of the gauge pipe into the dome 2. The valve 16 is actuated by a stem 17.

It will be understood that all the valve stems and lines passing through plate 3a are so installed as to prevent escape of vapors from or access of air to the tank car.

A charging line of the usual type is provided, 65 together with a bottom draw-off valve 19. The construction and use of these devices as such form no part of the present invention.

As shown in Fig. 2, valve box 3 has a cover 20. There is also an inner cover 21 over a manhole 22 70 in base plate 3a.

A look box or other suitable indicating device 23 is connected with vent line 6, which leads to a gas storage tank in the ordinary way.

The operation of the device is as follows, refer- 75 ring for example to the handling of casinghead gasoline:

The gasoline is pumped into the tank car shell 1 through line 4. Valves 5, 7, 11, 16 are open and plug 14 is closed. The gasoline rises in the 80 shell, line 6, and gage pipe 10. As soon as the gasoline has risen above the lower end of the small pipe 8 a pressure is developed in the closed shell which causes the liquid to rise rapidly through the small pipe into look box 23. The 85 operator can then see that the car is loaded shellful.

The car can be gaged and sampled through the gage pipe 10 without permitting substantial escape of vapor. Valves 5 and 7 are closed. Valve 90 11 in the bottom of the gage pipe is closed, thus preventing any pressure existing in the tank from acting upon the liquid in the gage pipe, and valve 16 is also closed. This seals the car. Then the plug 14 is partly screwed out to relieve pressure 95 through perforations 15. When the pressure is relieved, the plug is removed and the liquid gaged in the usual way by inserting a gaging rod. A ring 24 is set in the pipe at the level of the top of the shell to aid in gaging. Samples 100 may be taken as desired.

With the construction described it is unnec- 105 essary to open the dome cover at any time during the loading, gaging or unloading of the tank. In this way the dangers and losses incident to escape of volatile vapors into the air are avoided.

The construction described is illustrative only and various changes may be made within the scope of the appended claims, in which it is my 110

intention to claim all novelty inherent in the invention as broadly as the prior art permits.

I claim:

- 5 1. In combination with a receptacle for volatile liquids, a loading line for supplying liquid to the receptacle and a vent line for conveying gas therefrom, a pipe within the vent line and terminating at about the top of the storage space of the receptacle, means for causing the liquid to rise through said last mentioned pipe when the receptacle has received a predetermined amount of liquid a gage pipe having a removable closure, and means for isolating the gage pipe from the body of the receptacle.
2. In combination with a receptacle for volatile liquids, a loading line and a vent line having a look box therein at a point outside the receptacle, the vent line extending downwardly to open within the lower part of the receptacle and secured at its lower end to the receptacle, a small pipe within the vent line opening into the look box and terminating near the top of the storage space of the receptacle, the vent line having an opening above the lower end of the small pipe, and means for causing liquid to rise

through the small pipe into the look box when the receptacle has received the proper amount of liquid.

3. In combination with a receptacle for volatile liquids, a gage pipe extending to a point near the bottom of the receptacle, a valve in a branch pipe supported by the upper portion of the gauge pipe and a valve in the lower portion of the gauge pipe, a hollow screw plug normally closing the upper end of the gage pipe, said plug having openings adapted to place the pipe in communication with the atmosphere when the plug is partly unscrewed.

4. In combination with a tank car having a dome, a cover for the dome, a gage pipe extending from the cover to a point adjacent the bottom of the car, a valve in a branch pipe supported by the upper portion of the gauge pipe and a valve in the lower portion of the gauge pipe, means normally closing the gage pipe at the upper end but operable to vent it to the atmosphere when the valves are closed, and means for charging liquid into the car and for withdrawing liquid therefrom.
